UNITED STATES PATENT OFFICE.

RAY C. HIMEBAUGH, OF BURR OAK, MICHIGAN, ASSIGNOR TO ADELBERT C. HIMEBAUGH, OF BURR OAK, MICHIGAN.

DESIGN FOR A STAFF FOR HAND-PLANTERS.

46,736.

Specification for Design.

Patented Dec. 8, 1914.

Application filed August 27, 1914. Serial No. 858,985. Term of patent 14 years.

To all whom it may concern:

Be it known that I, RAY C. HIMEBAUGH, a citizen of the United States, residing at Burr Oak, in the county of St. Joseph, State of Michigan, have invented a new, original, and ornamental Design for a Staff for Hand-Planters, of which the following is a specification, reference being had to the accompanying drawing, forming a part thereof, in which—

Figure I is a front perspective view and Fig. II is a rear perspective view of a staff for hand planters, showing my new design.

I claim:

The ornamental design for a staff for hand planters, as shown.

RAY C. HIMEBAUGH.
